(57) **CLAIM**

We claim the ornamental design for a tip protector, as shown
and described.

DESCRIPTION

FIG. 1 is a perspective view of a tip protector of the new
design;

FIG. 2 is a right-side view thereof;

FIG. 3 is a left-side view thereof;

FIG. 4 is a front view thereof;

FIG. 5 is a rear view thereof;

FIG. 6 is a top view thereof; and,

FIG. 7 is a bottom view thereof.

The evenly-dashed broken lines in the drawings illustrate the
portions of the design that form no part of the claimed
design. The dash-dot broken lines in the drawings define the
bounds of the claimed design and form no part thereof.
